UNITED STATES PATENT OFFICE.

CHARLES A. SINGER, OF ST. LOUIS, MISSOURI, ASSIGNOR TO SINGER AUTO TRAFFIC SIGNAL COMPANY, OF ST. LOUIS, MISSOURI, A CORPORATION OF DELAWARE.

TRAFFIC-DIRECTING SIGNAL FOR VEHICLES.

1,321,254.

Specification of Letters Patent. Patented Nov. 11, 1919.

Application filed January 2, 1917. Serial No. 140,132.

To all whom it may concern:

Be it known that I, CHARLES A. SINGER, a citizen of the United States, residing at St. Louis, Missouri, have invented a certain new and useful Improvement in Traffic-Directing Signals for Vehicles, of which the following is a full, clear, and exact description, such as will enable others skilled in the art to which it appertains to make and use the same.

This invention relates to traffic-directing signals for vehicles of the type that comprise an electrically-operated "stop" indicator which becomes operative automatically when the driver operates the device that controls the brake on the vehicle.

The main object of my invention is to provide a circuit controlling switch for a traffic-directing signal of the character referred to which is so designed that it can be set or adjusted to cause the "stop" indicator to act automatically only when the brake controlling device is actuated sufficiently to tightly set or clamp the brake, thereby enabling the brake of the vehicle to be partially applied without causing the "stop" indicator to operate automatically.

Figure 1 of the drawings is a diagrammatic view, illustrating a traffic-directing signal equipped with a circuit-controlling switch constructed in accordance with my invention, the steering column and the foot brake lever of the automobile on which the signal is used being shown in side elevation.

Fig. 2 is a horizontal sectional view, taken on the line 2—2 of Fig. 1, looking in the direction indicated by the arrows.

Fig. 3 is a vertical longitudinal sectional view of my improved controlling switch that is combined with the foot brake lever to effect the automatic operation of the "stop" indicators.

Fig. 4 is a side elevational view, illustrating a slight modification of my invention.

Fig. 5 is a top plan view of the switch illustrated in Fig. 3, the foot brake lever being shown in horizontal section; and

Fig. 6 is a vertical transverse sectional view, taken on the line 6—6 of Fig. 5.

I have herein illustrated my improved switch applied to a traffic-directing signal of the kind that comprises two sets or groups of similar indicators arranged so that they can be seen from the front and from the rear of the vehicle on which the signal is

installed, electrically-operated devices for actuating said indicators and a hand switch for governing the various circuits in which said electrically-operated devices are arranged. The particular type of signal with which the switch is used is immaterial, however, so far as my present invention is concerned.

As shown in Fig. 1, the complete signal comprises two groups or sets of indicators arranged at the front and at the rear of the vehicle, each of said groups being made up of a normally operative indicator 1 provided with the word "Ahead", or some other suitable indicia for denoting the normal direction of travel of the vehicle, three indicators 2 provided with the words "Right", "Left" and "Back", respectively, or other suitable indicia, for denoting proposed changes in the direction of travel of the vehicle, and an indicator 3 provided with the word "Stop" or other suitable indicia, to indicate that the vehicle will slow down or stop. Each group of indicators is arranged in a housing that is provided with a sight opening, and solenoids or other suitable electrically-operated devices are arranged inside of said housing for actuating devices that are operatively connected with the indicators 2 and 3 in such a manner that said indicators will be moved into operative position, or, in other words, into alinement with the sight opening in the housing when the devices are energized and will be restored to an inoperative position when said devices are de-energized. An electric lamp 5 or other suitable illuminating device is arranged inside of the housing above referred to and the words or indicia on the indicators are formed from transparent material, so that the words on the indicators can be seen plainly at night. The electric circuits in which the solenoids are arranged are governed by a hand switch D of any preferred type that is arranged in such a position that it can be actuated easily by the driver of the vehicle, the switch D herein illustrated being mounted on the steering column, as shown in Fig. 1.

The controlling switch previously referred to that forms the subject-matter of my present invention, governs the automatic operation of the "stop" indicators 3 at the front and rear of the vehicle and consists of a plunger type switch E that is com-

bined with the foot brake lever F of the automobile. Said switch E is provided with two spring contacts 10 and 11, as shown in Fig. 5, a plunger 12 having an insulated 5 end portion 12^a, as shown in Fig. 3, that is adapted to be moved into engagement with the contacts 10 and 11, so as to close the circuit in which the switch is arranged, and a coiled spring 13 for moving said plunger 10 12 in a direction to break the circuit, said spring 13 being preferably arranged in a pocket 14 formed in a block of insulating material 15 that carries the contacts 10 and 11 and the plunger 12, as shown in Fig. 3. 15 A substantially bell-crank-shaped lever 16 that is pivotally mounted on an horizontally-disposed shaft 17 carried by bearings 18 on the block of insulating material 15 serves to limit the outward movement of the 20 plunger 12, namely, movement in a direction to break the circuit in which the switch E is arranged, said lever 16 having a depending arm that laps over the head at the outer end of the plunger 12 and a forwardly-projecting arm that bears against the block of insulating material 15 when the plunger 12 is in its outward position, as shown in 25 Fig. 3. Various means may be employed for forcing the plunger 12 inwardly, so as 30 to close the circuit controlled by the switch. The means shown in Fig. 3 for effecting this movement of the plunger consists of a lever G arranged in such a manner that one end of same will engage the forwardly-projecting arm of the bell crank lever 16 and rock said lever 16 in a direction to push the plunger 12 forwardly, or to the left, looking at Fig. 3, when the opposite end of said lever G is depressed by the downward movement 35 of the foot brake lever F. The lever G is preferably formed from a piece of spring steel wire that is looped around the shaft 17 and bent to form two portions that lie on opposite sides of the shaft 17, namely, 40 45 a rear portion consisting of a bail through which the foot brake lever F passes, and a front portion consisting of a short arm that lies under the forwardly-projecting arm of the bell crank lever 16. When the foot 50 55 brake lever F is moved downwardly, the foot portion 19 at the upper end of said lever engages the cross piece of the bail on the lever G and moves the right hand end portion of said lever G downwardly, there- by rocking the bell crank lever 16 and caus- ing the insulated portion 12^a at the inner end of the plunger 12 to come into engage-

ment with the contacts 10 and 11. When the foot brake lever moves upwardly, the spring 13 moves the plunger 12 outwardly, 60 thereby disengaging the insulated portion at the inner end of same from the contacts 10 and 11 and also restoring the levers 16 and G to normal position. One advantage of forming the lever G from a piece of spring 65 steel wire that is looped around the shaft 17 in the manner shown is, that said lever will give or yield slightly, in case the plunger 12 reaches its extreme inward position before the foot brake lever F reaches its extreme 70 downward position, thereby preventing breakage of the lever G. And still another desirable feature that results from forming the lever G in this manner is, that the bail portion of said lever can be bent into such a 75 position that said lever G will be actuated only when the foot brake lever is forced away down, or, in other words, depressed sufficiently to tightly set or clamp the brake controlled by same, thereby enabling the driver to partially apply the brake without effecting the automatic operation of the "stop" indicator. The position of the lever G with relation to the foot portion 19 at the 80 upper end of the foot brake lever F can also be varied by simply shifting the switch E toward or away from the portion of the foot brake lever F that projects upwardly through the foot board of the automobile. 85

Having thus described my invention, what I claim, and desire to secure by Letters Patent, is:

1. In an automobile, the combination of a foot brake lever, a circuit controlling switch, and a resilient lever arranged between said foot brake lever and said switch for actuating said switch and adapted to be bent so as to permit the foot brake lever to move a certain degree without operating said switch. 90
2. In an automobile, the combination of a foot brake lever, a circuit controlling switch, and an actuating member for said switch formed of spring steel wire or material of a similar nature and provided with a bendable portion through which said foot brake lever passes. 95
3. In an automobile, the combination of a foot brake lever, and a circuit controlling switch provided with a bail-shaped actuating member through which the foot brake lever passes. 100

CHARLES A. SINGER.
